United States Patent Office.

LEWIS H. BAKER, OF TARRYTOWN, NEW YORK.

Letters Patent No. 79,050, dated June 23, 1868.

IMPROVED LOUNGE.

The Schedule referred to in these Letters Patent and making part of the same.

TO ALL WHOM IT MAY CONCERN:

Be it known that I, LEWIS H. BAKER, of Tarrytown, in the county of Westchester, and State of New York, have invented a new and improved Convertible Lounge; and I do hereby declare that the following is a full, clear, and exact description thereof, which will enable those skilled in the art to make and use the same, reference being had to the accompanying drawings, forming part of this specification.

This invention relates to the construction of lounges or sofas, whereby they are made to serve various purposes, and are made much more convenient as an article of household furniture than the ordinary kind; and it consists in so forming the lounge, and combining the parts of which it is composed, that provision is made for forming a double bed, with space for the bed-clothing when not used as a bed, and for an adjustable wash-stand and drawer, as will be hereinafter more fully described.

Figure 1 is a longitudinal view of the lounge, which, as represented, appears the same as the ordinary furniture-lounge.

Figure 2 represents the lounge open, as when being prepared as a double bed.

Figure 3 is a view of the head end of the lounge, as when open, and with the adjustable wash-stand extended and ready for use.

Similar letters of reference indicate corresponding parts.

The body of the lounge is formed in two longitudinal parts or sections, which are hinged together at the back side, so that the back of the lounge A can be thrown back, as represented in fig. 2.

B are the hinges by which these parts are connected.

C is the lower or stationary part, to which the legs C' of the lounge are attached.

D is another section, which is enclosed in C when the lounge is closed up, but which is hinged to the front of C, so that it can be turned over in front when the part A is turned back, as represented in figs. 2 and 3.

E represents the hinges by which C and D are connected together.

When the section D has been turned over, as seen, the part A is turned back to its original position, forming one part of the bed, while D forms the other part.

F is a head-piece, which is pivoted to the end of D, so that it may be folded down on to the top of D when the lounge is closed, and thrown back, as seen in fig. 3, when the lounge is open.

This head-piece is supported by stay-rods, g, which are so formed that when the head-piece is thrown back it is supported on shoulders formed on the rods, which bear on the top of the part D, substantially as seen.

h represents two or more legs, which are pivoted to D, and which fold up into recesses prepared for them in the under edge of the front piece.

When the lounge is extended, as seen in fig. 3, these legs drop down from their recesses, and support the part D, as seen.

J represents the wash-stand.

Jointed legs, k, are attached to its bottom, and to the floor of the recess, in which the stand rests when the lounge is closed.

When the lounge is open, the wash-stand may be raised by extending the jointed legs k, as seen in fig. 3.

m are braces attached to the legs, for the purpose of steadyng the wash-stand when it is raised, as represented.

L represents a drawer beneath the foot-end of the lounge, in which to keep towels or other necessary articles.

Between the parts of the lounge, when they are folded together, there are recesses of sufficient capacity to contain the pillows and bed-clothing.

The seat and back of the lounge may be upholstered in the usual manner.

It will thus be seen that by a lounge constructed according to my invention, and as described, the most of the necessary articles of furniture for a bedroom are provided.

For small rooms or tenements, the advantages of this arrangement must be obvious to all.

Having thus described my invention, I claim as new, and desire to secure by Letters Patent—

In combination with a furniture-lounge, an extension or folding wash-stand, arranged and operated substantially as described.

The above specification of my invention signed by me, this 16th day of February, 1868.
